UNITED STATES PATENT OFFICE.

HENRY E. MUCHNIC, OF ATCHISON, KANSAS.

PACKING-RING.

1,200,641.

Specification of Letters Patent. Patented Oct. 10, 1916.

Application filed June 19, 1914. Serial No. 846,071.

To all whom it may concern:

Be it known that I, HENRY E. MUCHNIC, a citizen of the United States, residing at Atchison, in the county of Atchison and State of Kansas, have invented certain new and useful Improvements in Packing-Rings, of which the following is a specification.

This invention relates to improvements in packing rings, and has for its object to provide a new and improved form of packing ring comprising a plurality of sections.

Another object consists in providing means for maintaining said sections in operative position and in locking the same against relative displacement.

Still another object consists in providing a construction of the character described above of such nature that a steel spring, rod, or the like may be utilized to maintain the packing ring sections in operative position and to lock the same against displacement, this spring and the sections being arranged so as to protect the former from the effects of heat when used in a cylinder or the like.

These and other objects will be set forth and described in the following specification and shown in the accompanying drawing, in which:

Figure 1 is a perspective of one embodiment of my invention; Fig. 2 is a plan view of the same; Fig. 3 is a side elevation thereof; Fig. 4 is a transverse section along the line 4—4 of Fig. 2; Fig. 5 is a similar section of a slight modification; Fig. 6 is a similar view of another modification.

It will be seen that each of these figures shows two complementary rings made up of sections, the rings being brought together face to face and each being provided with a groove, the opposing grooves forming a seat or inclosure for an expanding member.

Like numerals refer to like elements throughout the drawings, in which—

10 designates generally a packing ring comprising a plurality of sections 10^a—10^b. Each of the sections 10^a comprises a segment of a complete ring and is laid end to end with the similar sections. The same is true of sections 10^b. I have found it advisable 50 to overlap sections 10^a with respect to 10^b, as is clearly shown in Fig. 1, so that the possibility of leakage through the end contacts is greatly reduced, as will be apparent.

To prevent relative rotation of one side of 55 the ring sections with respect to the other side, I provide a small block 10^c which I

fasten by means of rivets 11, or the like, to the underside of one of the rings 10^a, see Figs. 1 and 3, for example. This block 10^c is of a thickness substantially identical with 60 the rings 10^b, the latter being constructed to leave sufficient space for the seating of this block 10^c when the device is assembled. It will be apparent that this block 10^c being secured to one of the rings 10^a will prevent 65 relative rotation of the rings 10^b with respect to rings 10^a when in assembled relation. In the form of device shown in Figs. 1 to 6, inclusive, I construct each of the sections on one side thereof with a groove 10^e, 70 these grooves in sections 10^a—10^b alining when the device is assembled to provide a single groove or seat. A spring member 12 comprising a rod, in the form shown, is of a contour substantially identical to that of 75 the groove mentioned above and is adapted to seat therein, as shown in the drawing. This rod substantially fills the groove and serves a double purpose. In the first place it is in effect a split ring or rod of spring 80 metal, such as steel, and is constructed and arranged to normally force the sections of the ring outwardly so that when they are located in a cylinder or similar place this rod will serve to maintain them in close en- 85 gagement with the wall of such cylinder; being constructed of spring metal for that purpose, at the same time being located in the groove, as shown most clearly in Figs. 4 and 6, it will prevent lateral displacement 90 of sections 10^a relative to sections 10^b, serv- 95 ing as a locking member when the ring is seated in its groove or seat, as for example, on a piston, it being understood that the separation of ring sections 10^a, 10^b will be 100 prevented by such groove or seat. An ad- 105 vantage of the construction described and shown is that it will not only serve as a lock- 110 ing and expanding member, but by the ar- 115 rangement and location of the groove shown, the rod or spring member 12 is substantially protected from the influence of the heat of a cylinder of similar location by being sub- 120 stantially inclosed by the packing ring sec- 125 tions. By this means I am enabled to con- 130 struct the packing ring sections of gray iron 135 or other heat resistant metal while I may utilize steel or other metal capable of use for 140 spring tension without much danger of the latter being deprived of its temper. This 145 is a very meritorious feature of my inven- 150 tion and it deserves considerable emphasis,

Still another advantage of this construction is that should one or several of the packing ring sections break or crack, the major portion of the ring will still be held 5 in operative position and will continue to perform its functions in a satisfactory manner.

In Fig. 5 I have shown a form slightly changed from that shown in Fig. 4 in that 10 the shape of the grooves 10° is substantially rectangular, the contour and cross section of the rod 12' being correspondingly changed.

In Fig. 6 I have shown still another 15 change in which elongated grooves 10" are provided and a rod 12" of similarly changed cross section is amplified.

The herein described invention, including 20 a packing ring composed of a plurality of complementary rings, each formed of a plurality of segments with associated features, is claimed broadly in my co-pending divisional application, Serial No. 76,121, filed February 4, 1916.

It is obvious that the invention as 25 described in the appended claims may, by the skilled constructor, be modified without the exercise of invention, such modification being within the scope of said appended claims.

30 What I claim is:—

1. A packing ring comprising a plurality of complementary rings placed side by side and in contact, each of said complementary rings being grooved on its contacting face and formed of a plurality of independent arc-shaped segments placed end to end, and an expanding member adapted to seat loosely in an inclosure formed by the co-operating annular grooves of said rings, 40 whereby radial displacement of said segments is prevented.

2. In combination, a plurality of similar sections placed end to end to form two expansible rings that contact laterally to form 45 a packing ring, each of said expansible rings having an annular groove on its contacting face the two grooves co-operating to form an annular seat, and a split or divided ring adapted to fit freely in said seat and distant 50 from the wearing surface of the packing ring to maintain all the sections in operative position.

3. A packing ring comprising a plurality of complementary rings placed side by side 55 and in contact, each of said complementary rings being annularly grooved and formed of a series of independent arc-shaped segments placed end to end, and an expanding member adapted to loosely seat in the co-operating annular grooves of said complementary rings, and to be distant from the wearing surfaces of said rings.

4. In combination as a piston packing ring, a plurality of similar sections placed

end to end to form two expansible rings 65 which contact laterally, each of said expansible rings having an annular groove in its contacting face, the two grooves co-operating to form an annular seat, and an expanding member freely seated in said groove 70 whereby to force the sections outwardly in engagement with the wall of the cylinder to maintain them in operative position.

5. A packing ring comprising a pair of complementary rings placed side by side and 75 in contact, said rings each being formed of a plurality of similar independent arc-shaped segments placed end to end and each having a groove formed in the contacting face thereof near the inner periphery of the 80 same, said grooves together forming a continuous circular seat, and a slit or divided circular elastic ring fitting in said circular seat to force outwardly and maintain all the segments in operative position and prevent displacement of the same.

6. A packing ring comprising a plurality of grooved complementary rings placed side by side and in contact with the grooves uniting, said complementary rings being each 90 formed of a plurality of independent arc-shaped segments placed end to end, the segments of one complementary ring overlapping those of the adjacent complementary ring, an expanding member seated in said 95 co-operating grooves in the complementary rings to maintain the segments in operative position, and means fixed on one complementary ring and engaging the other to prevent relative rotative movement of said 100 rings.

7. A packing ring comprising a plurality of complementary rings placed side by side and in contact, each of said complementary rings being formed of a series of independent arc-shaped grooved segments placed end to end and therefore as a whole annularly grooved, and an expanding member adapted to loosely occupy the complete groove of the assembled complementary 110 rings and wholly within the body of the packing ring whereby, by the coaction between said expanding member and said segments the latter, regardless of the cracking or breakage of one or more thereof, are 115 maintained in operative position.

8. A packing ring comprising a plurality of complementary rings placed side by side and in contact, said rings being each formed of a plurality of independent arc-shaped 120 segments grooved at their meeting faces and placed end to end, and an expanding member adapted to be practically inclosed by and loosely seated in the co-operating annular grooves in the connecting faces of the 125 complementary rings, which expanding member, coacting with said segments, maintains the latter in operative position and

prevents displacement of the segments of one complementary ring with respect to those of the other complementary ring.

9. A packing ring comprising a plurality of complementary rings of gray iron or other heat resisting metal placed side by side and in contact, each of said complementary rings being formed of a plurality of independent arc-shaped grooved segments placed end to end, and an elastic circular rod of steel or the like seated in the continuous groove formed at the meeting parts of the

assembled complementary rings and away from the wearing surfaces of said rings, by which construction said rod is protected 15 from such heat as would otherwise deprive it of its temper.

In testimony whereof, I have subscribed my name.

HENRY E. MUCHNIC.
